UNITED STATES PATENT OFFICE.

PEDRO CELESTINO SACCAGGIO, OF TALLERES, FERRO CARRIL SUD, ARGENTINA,
ASSIGNOR TO J. STONE & COMPANY LIMITED, OF DEPTFORD, ENGLAND.

CAR-DOOR HINGE AND FASTENER.

1,154,061.

Specification of Letters Patent. Patented Sept. 21, 1915.

Application filed January 26, 1914. Serial No. 814,396.

To all whom it may concern:

Be it known that I, PEDRO CELESTINO SACCAGGIO, a citizen of the Argentine Republic, and resident of Talleres, Ferro Carril Sud, 5 Argentina, have invented new and useful Improvements in Car-Door Hinges and Fasteners, of which the following is a specification.

This invention relates to hinges and means 10 for securing the doors or hinged sides or ends of railway cars and other vehicles.

According to this invention the hinges of a vertically swinging door or the like the straps of which hinges preferably extend 15 from below the bottom of the door to near the top thereof are pivoted or hinged to the frame of the car and preferably to a bracket fixed to the sole plate or sole bar or other appropriate part of the vehicle, to which 20 bracket or part is also hinged or loosely connected at a lower level than the fulcrum of the hinge, one end of a strut or support the other end of which is connected to the hinge strap or the door in such a manner as to 25 allow both the hinge and the strut to turn freely on their respective fulcrua for opening and closing purposes without jamming or locking, suitable locking means being also provided for holding the said strut and with 30 it the door in the upright or closed position. The locking means may operate automatically to lock the strut during the last part of the closing movement of the door and preferably comprises a rotary cam which 35 may also be operated by a lever.

In order that the invention may be easily understood reference is made to the accompanying drawings in which:—

Figure 1 is a vertical transverse section 40 on the line I—I Fig. 2 of part of a railway freight car with a hinged or vertically swinging door provided with a hinge and strut made according to this invention. Fig. 2 is a side elevation and Fig. 3 is a 45 cross section of the hinge on the line III—III, Fig. 2. Fig. 4 is an enlarged view of parts of the locking or retaining device seen in Fig. 1. Fig. 5 is a front view of Fig. 4 and an enlarged view of parts seen in Fig. 2. Fig. 6 is a diagrammatic end elevation of a 50 railway car with the invention applied thereto. Fig. 7 is a vertical transverse section of part of a railway car with a modified construction of hinge and strut and Fig. 8 is a side elevation of same.

In carrying the invention into effect and as shown in Figs. 1 to 6, the bracket *a* is fixed to the outer vertical face of the sole plate *b* which may be of wood or of steel of *E* section or of other appropriate section and 60 the hinge strap *c* which as shown in Fig. 3 is suitably made *L* shaped in cross section with lateral flanges *d* *d* is fixed or bolted to the door *e* and hinged or pivoted to the upper lug *f* on the bracket *a*. The bracket is 65 moreover provided with a horizontal flange *g* which takes over and rests on the sole plate *b*.

The hinge strap *c* is suitably forked at the hinge end as indicated by the dotted 70 lines marked *h* in Fig. 2 and is connected to the hinge part or lug *f* on the upper part of the bracket *a* by a pintle *i*, the said lug or hinge part *f* having a projection or hooked portion *k* (see also Figs. 1, 4 and 5) 75 which is cleared by the hinge when the door is swung downward owing to the forked formation of the hinge. The lower part of the bracket *a* also has a hinge part or lug *l* thereon and a bent strut *m* with two flanges 80 *n* *n* is pivoted at its lower forked end by a pintle *o* to the said lug *l* and is disposed in front or outside of the hinge strap *c*. The axis of this pintle *o* suitably lies in the vertical plane which contains the axis of the 85 pintle *i* of the door hinge *c*, or the axis of the strut hinge may lie in a vertical plane in front of the axis of the door hinge. The upper part of the strut *m* is bent inward toward the door *e* and is suitably provided 90 with two inwardly projecting lateral lugs *p* (Figs. 1, 2 and 3) which loosely embrace the flanges *d* on the upper part of the hinge strap *c*, such lugs *p* being so constructed as to move freely on the hinge strap *c* and 95 without jamming against the door. The strut is also slotted as at *j* to allow it to pass over the hook *k*.

The pintles *i* and *o*, on which the door *e* and strut *m* are respectively mounted, are at 100 some distance from each other, the door when turned upward or downward describing an arc such as *q* (Figs. 1 and 6) while the strut describes an arc such as *r*. Consequently the connection between the door *e* and the strut *m* must be loose enough to permit the strut to slide on the hinge strap *c* *d* of the door when the latter is being raised or lowered. In order to lock the door in the 105 closed or upright position the flanges *n* of 110

the strut m are perforated and a forked lever s having trunnions t t , see Figs. 2, 4, and 5 is mounted on the strut by inserting the trunnions in the perforations. The hub portion u lying between the trunnions t t is cut away in the middle to form, for example, a half cylinder v which is hollow and which, when the lever s is hanging down as shown takes into the recess of the projection or hooked member k . If the lever s be raised, the semi-cylindrical portion v revolves and passes out of the recess or hook k aforesaid so that when the strut is turned outward the semi-cylindrical part v will clear the nose of the hook. Thus the strut m and with it the door e is then free to be swung down to the opened position of the door seen in dotted lines in Fig. 1. In this position the lever s hangs downwardly. When the door is raised for the purpose of closing it, the lever remains in a hanging down position for a time, but before the door reaches the upright or vertical position, the right-hand side of the cam v comes into contact with the hook k whereupon, owing to the continued closing movement of the door, the cam together with the lever s is forced to turn on the trunnions t in a clockwise direction, so that the lever assumes an elevated position and the cutaway portion of the hub u will allow the strut n to pass over the hook, the hollowed side of the cam v meanwhile being adapted to roll over the point of the hook. As soon as the door reaches the vertical position and the strut has passed over the hook k the door will be automatically locked because when the cam v has rolled to the inner side of the hook, such cam will be released and the handle s will drop of its own accord and bring the part v into the locking position shown clearly in Fig. 4.

According to a modification and as shown in Figs. 7 and 8, the strut is made of two double links w w and x x and instead of the strut being slidably connected to the hinge of the door e , it is hinged or pivoted to the lug z on the part y of the door hinge. The strut and the door are locked in position by a fastening such as hereinbefore described, the trunnions t in this case serving as the hinge pins connecting the links w w and x x together the parts being secured for example by washers 1 and pins 2. Other appropriate fastenings or locking devices may be employed however.

With slight modification the constructions hereinbefore described may be adapted to the ends of wagons which may fold or fall inward instead of outward.

What I claim is:—

1. The combination with the hinge of a vertically swinging car door, of a strut hinged at one end to the wagon at some distance from the fulcrum of the said hinge,

the other end of said strut being connected to the door in such manner as to allow the hinge and strut to turn about their respective axes and means for holding said strut and with it the door in the closed position. 70

2. The combination with the hinge of a vertically swinging car door, of a strut hinged at one end to the wagon at some distance beyond the axis of the said hinge, the other end of said strut being connected to the 75 door hinge in such a manner as to allow the hinge and strut to turn about their respective axes, a projection on the fixed part of the door hinge and locking means mounted on the strut and adapted to engage with and 80 be disengaged from said projection.

3. The combination with the hinge of a vertically swinging car door, of a strut hinged at one end to the wagon at some distance from the axis of the said hinge, the 85 other end of said strut being connected to the hinge in such a manner as to allow the door and strut to turn simultaneously about their respective axes, a projection on the fixed part of the door hinge and a locking 90 cam rotatably mounted on the strut and adapted to be engaged with and disengaged from said projection.

4. The combination with the hinge of a vertically swinging car door, said hinge 95 comprising a forked member pivoted to the fixed hinge part on the wagon, of a rigid strut hinged at one end to the wagon at some distance below the axis of the door hinge, and slidably connected at the other 100 end to the hinge in such a manner as to allow the door and strut to turn simultaneously about their respective axes, a projection on the fixed part of the door hinge, a locking cam rotatably mounted on the 105 strut and adapted to engage with said projection, and a lever connected with said cam and adapted to disengage the latter from said projection.

5. The combination with the hinge of a 110 vertically swinging car door, said hinge comprising a forked member pivoted to the fixed hinge part on the wagon, of a rigid strut hinged at one end to the wagon at some distance below the axis of the door 115 hinge, the other end of said strut having lugs, said lugs loosely and slidably embracing the hinge part on the door in such a manner as to allow the door and strut to turn simultaneously about their respective 120 axes, a projection on the fixed part of the door hinge, and a locking cam rotatably mounted on the strut and adapted to engage with said projection.

6. The combination with the hinge of a 125 vertically swinging car door, said hinge comprising a forked member pivoted to the fixed hinge part on the wagon, of a rigid strut hinged at one end to the wagon at some distance below the axis of the door 130

hinge, the other end of said strut having lugs, said lugs loosely and slidably embracing the hinge part on the door in such a manner as to allow the door and strut to 5 turn simultaneously about their respective axes, a projection on the fixed part of the door hinge and a lever having a cam of semi-cylindrical and hollow form such lever being rotatably mounted on the strut for engaging the cam with and disengaging it 10 from said projection.

7. The combination with the hinge of a vertically swinging car door, of a rigid strut having lateral flanges and hinged at one end 15 to the wagon at some distance from and below the axis of the door hinge, the other end

of said strut having lugs, said lugs loosely and slidably embracing the hinge part on the door in such a manner as to allow the door and strut to turn simultaneously about 20 their respective axes, a projection on the fixed part of the door hinge and a lever having trunnions mounted in bearings in the flanges of the strut, a hollow semi-cylindrical cam situated between and connected with said trunnions and adapted to engage with and be disengaged from the 25 said projection.

PEDRO CELESTINO SACCAGGIO.
